31 Claims. (Cl. 200—50)

ABSTRACT OF THE DISCLOSURE

Circuit interrupter means on a door of metal enclosed switchgear is connected in series with switch blade means interlocked with the door which can be opened only when the switch blade means is in open position.

This invention relates to metal enclosed switchgear. It constitutes an improvement over the metal clad switchgear shown in U.S. Beebe et al. Patent 3,055,996 issued Sept. 25, 1962.

Among the objects of this invention are: To mount circuit interrupter means such as one or more fuses on a door of a metallic housing of compact design and arrangement for connection in series with one or more switch blades in the housing and to interlock the door and the switch blade or blades to permit opening of the door and making accessible the circuit interrupter means only when the switch blade or blades are in the open position; to make the circuit interrupter means, such as the fuses, so accessible that they can be removed and replaced without requiring the use of special fuse handling tools; to provide for manually operating latch means for the door and to interlock this latch means with the switch blade or blades; to mount the switch blade or blades on a rotatable shaft having a locking cam with which a locking lever cooperates and to interconnect the locking lever with a pawl that cooperates with latch means on the door; to interlock the door and the switch blade operating means thereby requiring that the latter occupy a predetermined position before the door can be opened and access can be had to fuses mounted on the door; to mount the switch blade or blades for rotation about a horizontal axis with the door carrying the fuses hinged about a vertical axis in one embodiment and about a horizontal axis in another embodiment; to employ circuit interrupter means in series with each switch blade for opening the circuit; to interpose movable and stationary insulating barriers between the fuse or fuses on the door and the switch blade or blades in the housing with registering openings therein through which connection is made therebetween and which openings are closed on opening of the door; to mount the movable barrier for horizontal translatory movement in one embodiment and for vertical translatory movement in another embodiment; to mount both the fuses and the separable contact circuit interrupter means on the door whereby they are deenergized and readily accessible when the door is opened; to provide for manually discharging energy stored in a spring operator where this action is required under certain operating conditions; in a compact fuse and switch design of the kind herein disclosed to provide for direct interlocking action between the fuses and the switch blades, between a handle for opening the door and the switch blades, and between the door handle and the switch blade operating mechanism; and to permit opening the door to afford access to the fuse and switch containing housing only after the switch blades have been moved to their open position and the switch blade spring operating mechanism has been discharged.

2

In the drawings: FIG. 1 is a view, in front elevation, of a cabinet for housing a disconnecting switch and fuse assembly. FIG. 2 is a view, somewhat diagrammatic in character, and taken generally along the line 2—2 of FIG. 1 to show the relation of the parts with the switch closed, the operating handle up and the door handle locked and in another part showing the relationship of the switch locking cam and the switch blade means to one of the fuses mounted on the door. FIG. 3 is a vertical sectional view, at an enlarged scale, taken generally along the line 3—3 of FIG. 1. FIG. 4 is a view, somewhat diagrammatic in character, and showing the relation of the parts with the switch open, the operating handle down, the spring mechanism discharged and the door handle free to move. FIG. 5 is a view, similar to FIG. 4, showing the relation of the parts with the switch locked open, the operating handle locked in the mechanism discharged position, and the door handle in the open position. FIG. 6 is a vertical sectional view taken generally along the line 6—6 of FIG. 1. FIG. 7 is a top plan view, at an enlarged scale, of one of the switch blade means shown in FIG. 6 in contact engagement with the upper contact finger of the fuse at one end and in engagement with the contact portion of the metallic adapter for the circuit interrupter means at the other end. FIG. 8 is a top plan view of the rotatable elongated porcelain insulator shown in FIG. 6 with the switch blade means mounted thereon, certain parts being shown in section. FIG. 9 is a vertical sectional view, at an enlarged scale, taken generally along the line 9—9 of FIG. 8 and looking from left to right. FIG. 10 is a view, in end elevation, of the switch blade assembly shown in FIG. 8 looking from right to left. FIG. 11 is a horizontal sectional view, at a slightly enlarged scale, and taken generally along the line 11—11 of FIG. 6. FIG. 12 is a vertical sectional view taken generally along the line 12—12 of FIG. 11. FIG. 13 is a vertical sectional view, at a slightly enlarged scale, taken generally along the line 13—13 of FIG. 1 with the operating handle shown by full lines in the switch open mechanism discharge position and by broken lines in the switch closed position. FIG. 14 is a view, in front elevation, and at an enlarged scale of the switch operating mechanism shown in FIG. 1, certain parts being broken away and other parts being shown in section. FIG. 15 is a vertical sectional view taken generally along the line 15—15 of FIG. 14. FIG. 16 is an elevational view of the locking cam for the switch handle. FIG. 17 is an elevational view of the switch mechanism position indicator. FIG. 18 is an elevational view of the mechanism toggle lever. FIG. 19 is an elevational view of the mechanism cam. FIG. 20 is an elevational view of the stop lever assembly. FIG. 21 is a vertical sectional view taken generally along the line 21—21 of FIG. 14. FIG. 22 is an elevational view of the operating lever. FIG. 23 is an elevational view of the toggle lever member having switch opening and closing arms. FIGS. 24, 25, 26, 27, 28 and 29 are views showing the different operating positions of the mechanism toggle lever, switch and mechanism position indicator and the mechanism cam. FIGS. 30, 31, 32 and 33 are views showing different operating positions of the switch operating handle interlock mechanism and the arrangement for manual discharge of the stored energy in the operating spring. FIG. 34 is a view, in side elevation, of the coupling lever cam, the coupling lever and the connecting pin therefor in disassembled relation. FIG. 35 is a vertical sectional view of a metallic closure having an alternate form of disconnecting switch and fuse with the fuse or fuses mounted on a door that is hinged about its horizontal axis. FIG. 36 is a vertical sectional view of still another embodiment of this invention in which both the fuse and the separable contact

circuit interrupter are mounted on the door for movement therewith to the open position.

In FIG. 1 the reference character 10 designates, generally, a metallic enclosure for switch gear. It includes a top connecting box 11 having therebelow a metallic circuit interrupting apparatus housing, indicated at 12, that is mounted on a bottom connecting box 13. These enclosures are formed preferably of sheet metal. The top and bottom connecting boxes 11 and 13 are provided for receiving conductor cables or bus bars for the purpose of making connections to and from the circuit interrupting apparatus mounted in the metallic housing 12. They may be of various heights and interchangeable with each other. The metallic housing 12 includes a front wall 14, a left side wall 15, a right side wall 16, and a rear wall 17, FIG. 6. The top connecting box 11 includes a top wall 18 and the bottom connecting box 13 includes a bottom wall 19 both of which are provided with suitable openings for the conductors, cables, bus bars, etc., as may be required. The top and bottom of the metallic housing 12 are open to permit the necessary connections to the circuit devices mounted therein.

The front wall 14 has mounted therein a door 22 that is arranged to rotate about a vertical axis. The door 22 includes upper and lower hinge extensions 23 and 24. Also, the door 22 is provided with a recess 25, FIGS. 1 and 2, in which a door handle 26 is mounted. In the closed and locked position of the door 22, the door handle 26 is located wholly within the recess 25 and no part of it extends beyond the surface of the door 22. The door handle 26 includes an upstanding flange 27 to facilitate its being gripped by the fingers of the hand of an operator. At its upper end the door handle 26 is mounted for rotation with a door handle shaft 28 that is journaled in the side walls of the door 22 defining the recess 25. A torsion spring (not shown) surrounds the shaft 28 and acts in a direction to bias the door handle 26 to the non-operated position shown in FIG. 1. A locking loop 29 extends through an opening 30 in the door handle 26 to receive a padlock for the purpose of preventing unauthorized operation.

Along the right side of the metallic housing 12 there is provided a recessed operating mechanism support 31 which includes overcenter spring means, indicated generally at 32 and described in detail hereinafter. A manually operable handle 33 is employed for operating the overcenter spring means 32 and it has a hand grip 34 to permit manual operation. In the upper and lower positions the manually operable handle 33 is wholly below the surface of the front wall 14. Likewise, the recessed operating mechanism support 31 and overcenter spring means 32 do not extend beyond the surface of the front wall 14.

As shown in FIGS. 1-5, manually operable door latch means 37 are employed in conjunction with the door handle 26 for controlling the opening of the door 22. As will appear hereinafter various interlocking mechanisms cooperate with the door handle 26 to prevent its movement to the unlocked position unless circuit switching apparatus in the metallic housing 12 occupies such position that it is safe for the operator to open the door 22. This is essential since relatively unskilled operators are likely to have access to the metallic housing 12. In accordance with this invention, for normal operation, it is not possible for the unskilled person who has access only to the metallic housing 12 by opening the door 22 to come into contact with any energized circuit parts.

The manually operable door latch means 37 includes a vertically movable latch bar 38 which is provided with vertical slots 39 through which pins 40 extend from a door flange 41. Latch hooks 42 extend inwardly from the latch bar 38 through openings 43 in a wall flange 44 of the metallic housing 12. The latch hooks 42 are arranged to engage latch plates 45 that are secured to the wall flange 44. For vertically moving the latch bar 38, a latch arm

46 is formed integrally with the door handle 26 and it carries a circular boss 47 that is positioned between the outstanding flanges of L-shaped brackets 48, one of which is shown in FIG. 3. On rotation of the door handle 26, 5 when it is free to rotate, the latch bar 38 is moved downwardly from the position shown in FIG. 2 to the unlatched position shown in FIG. 5. On reverse rotation of the door handle 26, the latch bar 38 is moved upwardly to the latched position.

10 For interlocking the operation of the door handle 26 with the circuit switching apparatus in the metallic housing 12, the latch arm 46 carries a detent 49 at its distal end that is provided with faces 50 and 51 which are arranged to be juxtaposed to faces 52 and 53 on a pawl 54 15 with the detent 49 being arranged to enter a notch 55 therein. The pawl 54 is pivoted on a pin 56 which extends from the side wall 15 and a torsion spring 57 is employed for biasing it in a clockwise direction as viewed in FIG. 2. The torsion spring 57 reacts between the pawl 20 54 and a pin 58 which extends from the side wall 15.

It is desirable to prevent opening of the door 22 unless the manually operable handle 33 is in the lower position in the recessed operating mechanism support 31 in contradistinction to the upper position shown in FIG. 1. Also, it is desirable that it be possible to open the door 22 only when switch blade means, to be described, in the metallic housing 12 occupies the open position. This control is effected by positioning the pawl 25 54 under the control of the position of the manually operable handle 33 and of the switch blade means. FIG. 2 shows the manually operable handle 33 in the upper position and the switch blade means in the closed position. The location of the pawl 54 then is such that its face 53 is juxtaposed to face 51 on the detent 49 thereby making it impossible to rotate the door handle 26 in a counter-clockwise direction to move the latch bar 38 downwardly and unlatch the door 22. For this purpose the pawl 30 54 is provided at one end with cable fastening means 61 to which a control cable 62 is secured intermediate its ends. One end of the control cable 62 extends through a stationary sleeve 63 to cable fastening means 64 carried at the distal end of a locking lever 65, FIG. 14. It will be understood that the showing in FIG. 2, as well as the showing in FIGS. 4 and 5, is somewhat diagrammatic in character and that, because of the flexibility of the control cable 62 and stationary sleeve 63, it is possible to locate the parts associated therewith in different planes from the plane of the drawing representing the relationship. The locking lever 65 is pivoted at 66 on the 35 recessed operating mechanism support 31 and it carries a circular pin 67 that is arranged to ride on periphery 68 of a handle locking cam 69 that is arranged to rotate with the manually operable handle 33. The handle locking cam 69 has a notch 70 one side of which is formed by a shoulder 71 for receiving the circular pin 67 as seen in FIGS. 4 and 5. When the manually operable handle 33 is rotated to the lower position represented in FIGS. 4 and 5, it, together with the torsion spring 57 operating through the control cable 62, rotates the locking lever 65 to position the circular pin 67 in the notch 70. In this position the handle locking cam 69 is prevented from rotating and, as long as the door 22 remains open and the pawl 54 remains in the position shown in FIGS. 4 and 5, it is not possible to move the manually operable handle 33 from its lower position.

40 The control cable 62 extends from the cable fastening means 61 through another stationary sleeve 72 and is secured by cable fastening means 73 to one end of a locking lever 74 that is pivoted at 75 on the side wall 65 45 as shown in FIG. 8. The other end 76 of the locking lever 74 is arranged to engage periphery 77 of a switch locking cam 78. A notch 79 is provided in the switch locking cam 78 having a shoulder 80 for receiving the end 76 as shown in FIGS. 4 and 5 which show the 50 position of the switch locking cam 78 when the switch

70 55

blade means occupies the open position. Particularly in FIG. 5 it will be observed that the end 76 is juxtaposed to the shoulder 80 and thus prevents rotation of the switch locking cam 78 and the switch blade means rotatable therewith as long as the pawl 54 remains in the position shown in FIG. 5. FIG. 4 shows an intermediate position in which the switch locking cam 78 is in the switch open position while the handle locking cam 69 and the manually operable handle 33 are being rotated to the lowermost position of the latter. In FIG. 4 the circular pin 67 is shown as entering the slot 70. Because face 50 on detent 49 opposes faces 52 on pawl 54, the pawl 54 cannot rotate. When the manually operable handle 33 occupies the position shown in FIG. 2, the switch blade means is closed and the locking levers 65 and 74 hold the pawl 54 in the position there shown with the face 53 opposite face 51 thereby making it impossible to move the door handle 26 to operate the latch bar 38 and unlock the door 22.

As shown in FIG. 6 the circuit interrupting apparatus within the metallic housing 12 includes one or more fuses, shown generally at 85, and mounted on the door 22 so that, when it is opened, they are readily accessible to the operator for replacing them. The fuse 85 may be of any suitable type such as the fuse shown in U.S. Lindell Patent 3,230,331, issued Jan. 18, 1966. However, other fuse constructions, such as current limiting fuses, can be employed. For single phase operation only one fuse 83 is mounted on the door 22 and it has switch blade means and a circuit interrupter therefor. A larger number, for example three fuses 85, can be employed in conjunction with a three phase circuit. The fuse 85 includes upper and lower fuse terminals 86 and 87 from which upper and lower contact fingers 88 and 89 extend. As shown in FIG. 7 the upper contact finger 88 is a vertical blade-like two part member which extends from the upper fuse terminal 86 and is provided with outturned foot portions 90 to provide latching contact engagement with contact members to be described. The lower contact finger 89 is a horizontal blade-like member and has a head portion 91 at its distal end for contact engagement with a stationary line terminal to be described.

For mounting the fuse 85 on the door 22, brackets 92 are secured, as by bolting, to its inner side for carrying insulators 93. The upper insulator 93 carries a fuse clip 94 for receiving the upper fuse terminal 86. Since the current path to the upper fuse terminal 86 is through the upper contact finger 88, it is unnecessary for the fuse clip 94 to be formed of good conducting material since it carries no current. A spring biased latch 95 is rotatably mounted on the fuse clip 94 and is arranged to engage a nut on the upper end of the upper fuse terminal 86 for holding the fuse 85 in position. The lower fuse terminal 87 is provided with a fitting 96 for receiving a hook 97 that is carried by the lower insulator 92. It will be understood that other fuse mounting arrangements can be used.

As pointed out, more than one, for example three, fuses 85 can be employed. Associated with each fuse 85 is stationary contact means, shown generally at 100, in FIGS. 6 and 7. The stationary contact means 100 in each instance is mounted on an insulator 101 that is carried by a transverse channel 102 which extends between the side walls 15 and 16 of the metallic housing 12. A terminal pad 103 extends upwardly to permit connection to a bus bar or cable in the top connecting box 11. Also there is provided a terminal pad 104 that permits connection by a cable or bus bar extending upwardly from the bottom connecting box 13.

For interconnecting each fuse 85 and the stationary contact means 100 individual thereto, switch blade means, indicated generally at 105 in FIGS. 6-10, is employed. In FIG. 8 three switch blade means 105 are shown.

The switch blade means 105 are mounted for rotation with an insulator shaft that is indicated, generally, at 106. 75

The rotatable shaft 106 includes an elongated porcelain insulator 107 having corrugations to increase the creepage distance between the several switch blade means 105 and between them and ground. The porcelain insulator 107 has integral end projections 108. At the left end a cup shaped adapter 109 is joined to the end projection 108 and from it a stub shaft 110 extends into a bearing 111 that is carried by the side wall 15. The switch locking cam 78 is welded to the stub shaft 110.

At the right end of the porcelain insulator 107 a metallic sleeve 114 is secured to the end projection 108. A stub shaft 115 extends from the right end of the metallic sleeve 114 and it is journaled in a bearing, not shown, similar to the bearing 111 and mounted on the side wall 16. An operating arm 116 extends radially from the metallic sleeve 114 for connection to the overcenter spring means 32 in a manner to be described. An L-shaped arm 117 is secured to the metallic sleeve 114 for engaging shock absorber means also to be described.

FIGS. 7 and 8 show the details of construction of each switch blade means 105 which comprises a pair of switch blade members 118 that are formed of flat copper bars. For mounting the switch blade members 118 on the porcelain insulator 107 to rotate therewith, they are positioned in a metallic tube 119 which is arranged to extend through a transverse opening 120 in the porcelain insulator 107, there being an opening 120 for each switch blade means 105. The assembly is suitably secured in each opening 120 as indicated at 121.

Since it is desirable that the switch blade members 118 have some degree of flexibility at their ends, they are positioned in juxtaposed relation in the metallic tube 119 and spaced therefrom by spacers 122. Rivets 123 extend through the assembly at one end of the metallic tube 119 and are spaced from the ends of the switch blade members 118.

At the left end of the switch blade members 118, FIG. 7, arcuate interlocking contact members 124 are individually secured by screws 125. The contact members 124 have inwardly extending arcuate flanges 126 that are arranged to engage the outturned foot portions 90 on the respective upper contact finger 88. When the switch blade means 105 occupies the switch closed position, FIG. 6, the interlocking engagement between the upper contact finger 88 and the interlocking contact members 124 is such that, even if it might be possible to move the door handle 26 to unlatch the door 22, it would not be possible to open the door 22. Thus, it is necessary that the switch blade means 105 be rotated to disengage the interlocking contact members 124 from the upper contact fingers 88 to permit opening of the door 22. The arrangement is such that this can take place only when the circuit between the switch blade means 105 and the stationary contact means 100 has been opened.

In order to maintain the interlocking contact members 124 in engagement with the outturned foot portions 90 of the upper contact fingers 88 both electrically and mechanically, leaf springs 127 are employed. As shown in FIG. 7 the leaf springs 127 are bowed at the left end of the metallic tube 119 so as to react between the inner surface thereof and the outer surfaces of the switch blade members 118 adjacent the interlocking contact members 124. The leaf springs 127 extend between the spacers 122 and the switch blade members 118 and are held by the rivets 123.

The other ends of the switch blade members 118 are indicated at 130 and are spaced apart. The end portions 130 are biased toward each other by coil compression springs 131 that react between the outer surfaces of the switch blade members 118 and cup shaped washers 132 that are interconnected by a transverse pin 133. The inner surfaces of the end portions 130 are arranged to have contact engagement with a contact portion 134 of a metallic adapter 135 which forms an integral part of the stationary contact means 100.

It is desirable to effect the disconnection of the switch blade means 105 from the stationary contact means 100 without arcing when the circuit is to be interrupted while carrying current. For this purpose separable contact circuit interrupter means, shown generally at 136, is provided and is mounted on the metallic adapter 135. The separable contact circuit interrupter means 136 can be constructed as generally disclosed in U.S. Lindell Patent 2,644,878, issued July 7, 1953. It includes a movable contact 137 that, in circuit closed position, is in contact engagement with stationary contact means constituting an extension of the metallic adapter 135. Associated with the movable contact 137 is a trailer 138 of insulation that is arranged to be moved by an operating rod 139 of conducting material for opening the circuit. The operating rod 139 extends through a tubular insulator 140 into which the arc incident to opening of the circuit interrupter means 136 is drawn and confined by it and by the trailer 138. For moving the operating rod 139 through the tubular insulator 140, the former is connected to an arm 141 that is mounted to rotate with an operating shaft 142 which is journaled at its ends in a metallic housing 143 that extends from and is carried by the lower end of the tubular insulator 140. An opening arm 144 is secured to one end of the operating shaft 142 and is arranged to be engaged by an opening cam 145, FIG. 7, that is carried by one of the spaced apart end portions 130 of the switch blade members 119. The opening cam 145 is secured by rivets 146 to the end portion 130. At the other end of the shaft 142 there is secured a closing arm 147 that is arranged to be engaged by a closing cam 148 which is secured by rivets 149 to the other end portion 130 of the switch blade members 118. An exhaust opening 151 is formed in the metallic adapter 135. When the insulator shaft 106, which includes the porcelain insulator 107, is rotated in a clockwise direction as indicated by the arrow 152 in FIG. 6, the end portions 130 of the switch blade members 118 move out of contact engagement with the contact portion 134 of the metallic adapter 135 after the opening cam 145 engages the metallic housing 143 to transfer the current path to the circuit interrupter means 136. Thereafter the opening cam 145 engages the opening arm 144. The continued rotation of the shaft 106 in the clockwise direction, as caused by a relatively powerful operating spring to be described, causes the operating rod 139 together with the movable contact 137 to be moved rapidly to the open position to interrupt the circuit and to confine any arcing that may take place within the tubular insulator 140. The length of the arcuate interlocking contact members 124 is such that they do not disengage the outturned foot portions 90 of the upper contact finger 88 until after the circuit has been opened by the separable contact circuit interrupter means 136. In the open circuit positions the arms 144 and 147 occupy the positions shown by the dotted lines and the arm 141, to which the operating rod 139 is attached, is shown by similar means. On reverse rotation of the insulator shaft 106, the arcuate interlocking contact members 124 first have interlocking contact engagement with the outturned foot portions 90 of the upper contact fingers 88. This is followed by engagement of the end portions 130 of the switch blade members 118 with the contact portions 134 of the metallic adapters 135 which form parts of the stationary contacts 100. The circuit is completed when the end portions 130 of the switch blade members 118 make contact with the contact portion 134 of the metallic adapter 135. Since the closing cam 148 has a relatively long cam surface 148', the closing arm 147 is not engaged to rotate the arm 141 and move contact 137 to the circuit closed position until after the circuit has first been completed around the circuit interrupter 136. This arrangement is advantageous when the circuit is closed on a fault as a result of which the current flow may be relatively great and sufficient to damage or destroy the separable contact circuit interrupter 136 should it be closed first. One or more of the fuses 85 blow under these conditions to interrupt the circuit.

As shown in FIG. 6 the head portion 91 of each lower contact finger 89, which is a horizontal blade like member, is arranged to engage a bifurcated end 154 of a stationary line terminal 155 that may be formed by a pair of flat copper bars. The furcations have sufficient resiliency to make a good contact engagement with the juxtaposed surfaces of the head portion 91 on the lower contact finger 89. The stationary line terminal 155 is mounted on a line terminal pad 156 which is carried by an insulator 157. A transverse channel 158, extending between the side walls 15 and 16, carries the insulator 157. Connection to the line terminal pad 156 can be made by a flexible cable or bus bar extending upwardly from the bottom connecting box 13.

When the door 22 is swung to the open position, the operator can have access to the fuse or fuses 85 for replacing them when necessary. Under these circumstances it is desirable that the arrangement be such that it is impossible for the operator to come into contact with any energized parts within the metallic housing 12. For example, it should be impossible for him to come in contact with any energized part associated with the stationary contact means 100 or with the stationary line terminal 155. In accordance with the invention this safety arrangement is provided employing the construction shown in FIG. 11. Stationary insulating side barriers 159 and 160 are mounted on angles 161 that are secured to the side walls 15 and 16. The insulating side barriers 159 and 160 and the other insulating barriers to be referred to are formed of suitable insulating material. Extending between the guide barriers 159 and 160 is a stationary insulating front barrier 162 that is provided, FIG. 6, with upper and lower openings 163 and 164 through which the upper and lower contact fingers 88 and 89 project. The openings 163 and 164 are of such size and shape that the contact fingers 88 and 89 can be swung therethrough as the door 22 is swung from the fully closed to the open position.

For closing the upper and lower openings 163 and 164 in the stationary insulating front barrier 162 after the contact fingers 88 and 89 have been swung away with the door 22, there is provided a movable insulating barrier or shutter 165. It is slidably mounted by four screws 166 (only two being shown) that are carried by the stationary insulating front barrier 162 and extend through slots 167 in the movable insulating barrier or shutter 165. Upper and lower openings 168 and 169 are provided in the movable insulating barrier or shutter 165 that, as shown in FIGS. 6 and 11, register with the upper and lower openings 163 and 164 in the stationary insulating front barrier 162 when the door 22 is closed.

When the door 22 is swung toward the open position, as shown by broken lines in FIG. 11, the upper and lower contact fingers 88 and 89 are swung through the registering openings 163-168 and 164-169 and then the insulating barrier or shutter 165 is moved to the position shown by broken lines in FIG. 11. For this purpose a U-shaped member 171 is secured to the insulating barrier or shutter 165 for engagement by an upstanding distal end 172 of one arm 173 that forms a part of a bell crank lever indicated, generally, at 174. The bell crank lever 174 is pivoted at 175 on an upper wall 187, FIG. 12, of the cabinet hinge pocket 188. Another arm 176 of the bell crank lever 174 is provided with an arcuate slot 177 which opens at one end into a straight slot 178 for receiving a pin 159 that is carried by an arm 180, FIG. 12, which is arranged to rotate with a vertical shaft 181. The shaft 181 is square in cross section and extends through inner flanges of the lower hinge extension 24 and thus rotates conjointly with the door 22. The lower end 182 of the vertical shaft or door hinge pin 181 is cylindrical and is journaled at 183 in the bottom wall 19. The upper end of the vertical shaft 181 extends through a

cylindrical bearing 184 and is secured thereto by a transverse pin 185. The cylindrical bearing 184 is journaled at 186 in the extension 187 of the bottom wall 19.

The upper hinge extension 23 is journaled on the front wall 14 of the metallic housing 12 in a similar manner. The arrangement is such that the door 22 rotates about a vertical axis which is at right angles to the plane of the horizontal axis about which the shaft 106 rotates that carries the switch blade means 105.

During the initial portion of the rotation of the door 22 from the fully closed position shown in FIG. 11 toward the open position, the pin 179 in the straight slot 178 causes the bell crank lever 174 to rotate to the position shown by broken lines. Since the pin 179 rotates with the arm 180 conjointly with the door 22, it moves relative to the straight slot 178 until it reaches the arcuate slot 177. Then continued rotation of the door 22 and the pin 179 causes no further rotation of the bell crank 174 since the pin 179 moves along the arcuate slot 177. When the bell crank 174 has moved to the alternate position shown by broken lines, the insulating barrier or shutter 165 has moved to cover completely the upper and lower openings 163 and 164 in the stationary insulating front barrier 162. As long as the door 22 remains in the open position or in any position in which the pin 179 remains in the arcuate slot 177, the insulating barrier or shutter 165 is locked thereby in the closed position and it is not possible to move it to expose the upper and lower openings 163 and 164 in the stationary insulating barrier 162.

In order to prevent direct exposure between the several fuses 85 and between them and adjacent metallic grounded parts, fuse insulating barriers 190 are mounted on the inside of the door 22 as shown in FIG. 11. They are arranged to swing to the open position with the door 22 and, in the closed position, certain of them are arranged to be juxtaposed to barrier extensions 191 on the movable insulating barrier or shutter 165.

Interphase barriers 192, FIGS. 6 and 11, are provided between the adjacent switch blade means 105. As shown in FIG. 11 they extend rearwardly from the stationary insulating front barrier 162 from locations between furring strips 193 mounted thereon. There are also provided an upper interphase barrier 194 and a lower interphase barrier 195 on opposite sides of the intermediate switch blade means 105. To facilitate application and removal of the lower interphase barrier 195, it is pivoted on a transverse rod 196 that extends between the side walls 15 and 16, a slotted arrangement being provided to permit application and removal of the barrier 195 to and from the rod 196. Each set of interphase barriers 192, 194 and 195 defines an opening 197, FIG. 6, for surrounding the porcelain insulator between adjacent corrugations as seen in FIG. 8.

It is desirable to dissipate the kinetic energy remaining after sufficient energy has been used to rotate the switch blade means 105 to the open position shown in FIG. 13. For this purpose there is provided a dashpot 201 that is secured to a plate 202 which is carried by a mounting bracket 203 carried by the side wall 16. A piston 204 is slidable in the dashpot 201 and has a piston rod 205 extending outwardly therefrom. A return spring 206 is interposed between the piston rod 205 and the dashpot 201 for the purpose of biasing the piston 204 to the right end of the dashpot 201 and to absorb with the air in the dashpot 201 the remaining kinetic energy incident to movement of the switch blade means 105 to the open position. Rotatably mounted on the stub shaft 115 is a dashpot arm 207 that is arranged to engage the right end of the piston rod 205. A stop pin 208, carried by the mounting bracket 203, limits the movement of the dashpot arm 207 under the influence of the return spring 206. The dashpot arm 207 is arranged to be engaged by a foot portion 117' of the L-shaped arm 117 that is secured, as shown in FIG. 8, to rotate with the shaft 106 carrying the switch blade means 105.

For rotating the insulator shaft 106 and thereby the switch blade means 105 from and to the open position, the operating arm 116 that is secured to the metallic sleeve 114 which forms an integral part of the shaft 106 is connected, FIG. 13, by an adjustable link 211 to a switch operating or drive lever 212, FIG. 22. For arresting movement of the switch blade means 105 in a closing direction and in the fully closed position, the switch operating or drive lever 212 is provided with a stop arm 213 that is arranged to engage a stop 214 formed of impact material that is mounted on the bottom 216 of the housing for the recessed operating mechanism support 31. In FIG. 13 the position of the switch operating or drive lever 212 in the closed position is shown by broken lines. In this position the adjustable link 211 and the switch operating or drive lever 212 is in a toggle or slightly overcenter position, thereby insuring that the switch blade means 105 will remain in the fully closed position until the switch operating or drive lever 212 is rotated to break the toggle.

FIGS. 14-23 show the overcenter spring means 32 and certain details of its construction. As pointed out, the housing forming the recessed operating mechanism support 31 includes the bottom 216 of sheet metal having outwardly curved ends and side walls 217 and 218. In FIG. 14 it will be observed that the manually operable handle 33 is secured to an operating shaft 219 the ends of which are journaled in bearings 220 carried by the side walls 217-218. The manually operable handle 33 is secured to the operating shaft 219 through the agency of a spacer sleeve 221 that is fastened by a drive pin 222 to the shaft 219. At the right end of the operating shaft 219 a spacer sleeve 223 is secured by a drive pin 224 thereto. Secured to the spacer sleeve 223 is a mechanism cam 225, also shown in FIG. 19. A bearing washer 226 is interposed between the right end of the spacer sleeve 221 and a hollow shaft 227 that is journaled by needle bearings 228 for free rotation on the shaft 219. Rotatably mounted on the left end of the hollow shaft 227 is a sleeve 229 to which the switch operating or drive lever 212 is secured for conjoint rotation. A pivot pin 230, carried by the switch operating or drive lever 212, serves as a connection to one end of the adjustable link 211, FIG. 13.

Provision is made for rotating the hollow shaft 227 by a spring. For this purpose a mechanism toggle lever 231, FIG. 18, is secured to the right end of the hollow shaft 227 and it carries a pin 232 for connecting it to a bifurcated end 233, FIG. 15, of a spring operating tube 234. The spring operating tube 234 extends rearwardly through the bottom 216 of the recessed operating mechanism support 31 and through a spring housing extension 235 secured to the bottom 216. At the remote end the spring operating tube 234 extends through a fulcrum sleeve 236 which has a knife edge 237 that engages the end 238 of the spring housing extension 235. A coil compression spring 239 surrounds the spring operating tube 234 and it reacts between the fulcrum sleeve 236 and a stop ring 240 that is secured to the spring operating tube 234. In the discharged position of the coil compression spring 239, it and the spring operating tube 234 occupy either the position shown in FIG. 15 or an alternate position in the lower part of the spring housing extension 235 that is symmetrical with respect to the position here shown. The coil compression spring 239 is charged by rotating the mechanism toggle lever 231 to a central position in which a line interconnecting the axis of shaft 219 and the knife edge 237 passes through the axis of pin 232. The coil compression spring 239 is discharged to effect operation of the switch blade means 105 when the axis of the pin 232 moves past this line.

In order to rotate the mechanism toggle lever 231 to charge the spring 239, a rectangular operating pin 244 is provided on and extends laterally from the mechanism toggle lever 231. The operating pin 244 is arranged to be engaged by a shoulder 245, FIG. 19, of the mechanism

cam 225 to charge the spring 239 for operating the switch blade means 105 to the switch closed position. Another shoulder 246 is provided on the mechanism cam 225 for engaging the operating pin 244 to charge the spring 239 and effect movement of the switch blade means 105 to the open position. It will be recalled that the mechanism cam 225 is secured for rotation to the shaft 219 to which the manually operable handle 33 also is secured for conjoint rotation.

In order to transmit the force of the coil compression spring 239 for operating the switch operating or drive lever 212, in turn to rotate the shaft 106 and the switch blade means 105, a switch operating member 247, FIG. 23, is secured to the hollow shaft 227 for conjoint rotation therewith. The switch operating member 247 then rotates conjointly with the mechanism toggle lever 231. Switch closing and switch opening arms 248 and 249 extend from the switch operating member 247 and are arranged to engage, respectively, impact members 250 and 251 that are carried by an angle member 252 which is secured to the switch operating or drive lever 212. The switch closing arm 248 engages the impact member 250 for rotat- 10 ing the switch operating or drive lever 212 to move the switch blade means 105 to the closed position while the switch opening arm 249 at the other end of the switch operating member 247 is arranged to engage the impact member 251 to rotate the switch operating or drive lever 212 in the opposite direction to move the switch blade means 105 to the open position.

It is desirable that means be provided for indicating the various positions of the switch operating or drive lever 212 and thereby the position of the switch blade means 105, and the position of the mechanism toggle lever 231 and thereby indicating whether the coil compression spring 239 is charged or discharged. For this purpose an arcuate position indicator 253 is employed. It is shown in detail in FIG. 17. The arcuate position indicator 253 includes a semi-circular central portion 254 for application to the hollow shaft 227. It is secured in frictional engagement therewith by a semi-circular clamp 255 which is held in place by screws 256. This construction permits the arcuate position indicator 253 to be rotated relative to the hollow shaft 227. The periphery of the arcuate position indicator 253, bearing suitable indicia, is visible through a window 257, FIG. 1, in a cover 258 that is secured to the bottom 216 by screws 259.

For operating the arcuate position indicator 253 in accordance with the position of the switch operating or drive lever 212, it is provided with a relatively short arcuate slot 262 for receiving an indicator operating pin 263 that extends laterally from an arm 264 of the switch operating or drive lever 212. The position indicator 253 also is provided with a relatively long arcuate slot 265 for receiving an outturned end 266 of an indicator operating arm 267 which is carried by the mechanism toggle lever 231, FIG. 18.

In order to prevent operation of the manually operable handle 33 under normal operating conditions when the coil compression spring 239 is fully charged, stop lever 270, FIG. 20, is employed. As shown in FIG. 14 the stop lever 270 is rotatably mounted by a pin 271 which extends from the wall 218. A torsion spring 272 acts to bias the stop lever 270 in a counterclockwise direction as viewed in FIG. 15. The stop lever 270 carries a roller 273 that is arranged to engage the periphery 274 of the mechanism toggle lever 231, FIG. 18, and is held in such engagement by the torsion spring 272. The mechanism toggle lever 231 has shoulders 275 and 276 which are engaged by the roller 273 when the coil compression spring 239 occupies one or the other of the overcenter positions to which it is operated by the manually operable handle 33 for ultimately effecting operation of the switch blade means 105 from one position to the other. As long as the roller 273 engages the periphery 274 of the mechanism toggle lever 231 and is out of

engagement with either of the shoulders 275 or 276, the stop lever 270 is held in the position shown in FIG. 15 where a rectangular stop pin 277 carried thereby is out of the path of either of shoulders 278 or 279 that are carried by the mechanism cam 125, FIG. 19. When the roller 273 on the stop lever 270 is permitted to rotate under the influence of the torsion spring 272 into engagement with one or the other of the shoulders 275 or 276, the pin 277 is moved into the path of one or the other of the shoulders 278 or 279 on the mechanism cam 225 which is secured to rotate with the manually operable handle 33. It is prevented from being rotated while one or the other of these conditions obtains.

There may be certain instances where it is desirable 15 that the stop lever 270 be manually released to permit the coil compression spring 239 to be discharged. Such a condition might occur when the switch blade means 105 occupy the open position with the coil compression spring 239 in the overcenter charged position ready to 20 be released for operating the switch blade means 105 to the closed position. For this purpose a tail piece 280 extends from the stop lever 270 and is arranged to be 25 engaged by a push button 281, FIG. 15, that is slidably mounted in a socket 282 which is carried by the cover 258. A spring 283 reacts against the push button 281 to hold it in the non-operated position. A rotatable cover 284 is provided for preventing access to the push button 281 except by authorized personnel. Preferably a key operated lock (not shown) is employed to prevent rotation of the cover 284 from the closed position.

In order to latch the switch blade means 105 in either the closed or the open position, the switch operating or drive lever 212, which is connected by the adjustable link 211 thereto, is provided with a latch pin 286 that extends laterally from the stop arm 213, FIGS. 13 and 21 show by full lines the position of the switch operating drive lever 212 when the switch blade means 105 occupies the open position. Upper and lower latch levers 287 and 288 are pivoted at 289 and 290 on the inner side of the bottom 216 and are provided with latch hooks 291 and 292. Torsion springs 293 and 294 act to bias the upper and lower latch levers 287 and 288, respectively, to the latched position. The other ends 295 and 296 of the upper and lower latch levers 287 and 288 are arranged to be operated by a closing armature 297 and an opening armature 298, respectively, under the control of a closing coil 299 and an opening coil 300. It will be understood that suitable remotely controlled 40 circuits are provided for selectively energizing the coils 299 and 300 for effecting operation of the armatures 297 and 298, in turn, to rotate the latch levers 287 and 288 to the unlatched positions.

In addition to the coils 299 and 300, closing and opening push buttons 301 and 302, FIG. 21, are arranged 45 for manual movement of the armatures 297 and 298, respectively. The push buttons 301 and 302 are slidably mounted in sockets 303 and 304 which are carried by the cover 258. Springs 305 and 306 in the sockets 303 and 304 act to bias the push buttons 301 and 302 to the nonoperated positions.

The operation of the overcenter spring means 32 will be described in conjunction with the illustrations in FIGS. 14-21 which show certain relative positions of various parts as viewed from left to right of FIG. 14.

FIGS. 15, 24 and 25 illustrate the relationships when 50 the switch blade means 105 is open and the coil spring 239 is discharged. In FIG. 24 a portion of the manually operable handle 38 is shown by full lines. It will be recalled that it is connected to the mechanism cam 225 to rotate it. In order to charge the spring 239 for closing the switch blade means 105, the handle 33 is rotated in a counterclockwise direction carrying with it the mechanism cam 225. In FIG. 24 the manually operable handle 33 has been rotated to the broken line position 55 through about 45° from the fully open lowermost posi-

tion to bring shoulder 245 into engagement with operating pin 244 on the mechanism toggle lever 231 which, as shown in FIG. 15, is connected to the spring operating tube 234. Continued rotation of the manually operable handle 33 in the counterclockwise direction rotates the mechanism toggle lever 231 and compresses the spring 239. In FIG. 25 the switch opening arm 249 of the switch operating member 247 is illustrated in engagement with impact member 251 on angle member 252 that is secured to the switch operating or drive lever 212 which is connected, FIG. 13, by the adjustable link 211 to the operating arm 116 on the rotatable shaft 106 that carries the switch blade means 105. As a result of previous discharge of the spring 239, the switch operating member 247 had rotated the switch operating drive lever 212 to the position here shown and the switch blade means 105 to the open position. The latch hook 291 of the upper latch lever 287 is shown in latching engagement with the latch pin 286 that extends laterally from the stop arm 213 of the switch operating or drive lever 212. This arrangement latches the switch blade means 105 in the open position. The latch hook 291 must be unlatched to permit operation of the switch blade means 105 to the closed position. The indicator operating pin 263, that extends laterally from the switch operating or drive lever 212, had previously moved the arcuate position indicator 253 to the position shown in FIG. 25 where a section 308 thereof registers with the window 257 in the cover 258. This section 308 can bear indicia indicating that the switch blade means 105 is open and the spring 239 is discharged. The latter is indicated by the position of the outturned end 266 of the indicator operating arm 267 at the left end of the relatively long arcuate slot 265, the arm 267 being attached to the mechanism toggle lever 231.

FIGS. 26 and 27 show the relative positions of certain of the parts when the switch blade means 105 is open and the spring 239 has been compressed. In FIG. 26 the manually operable handle 33 is shown in its uppermost position and a corresponding movement of the mechanism cam 225 has taken place. The shoulder 245 in engagement with the operating pin 244 on the mechanism toggle lever 231 has moved the latter to the position here shown. For illustrative purposes it is pointed out that FIG. 26 shows the movement of the mechanism toggle lever 231 to a position about 15° past the center position where, referring to FIG. 15, the line interconnecting the axis of shaft 219 and the knife edge 237 passes through the axis of the pin 232. However, as shown in FIG. 27, the upper latch 287 has its latch hook 291 in locking engagement with the latch pin 286 on the switch operating or drive lever 212. Accordingly, the switch operating or drive lever 212 and the switch blade means 105 are prevented from rotating to the closed position. When the mechanism toggle lever 231 is rotated to the position shown in FIGS. 26 and 27, the switch operating member 247 is rotated to the position shown in FIG. 27 where the switch closing arm 248 engages the impact member 250 carried by the angle member 252 that is secured to the switch operating or drive lever 212. While the indicator operating pin 263 on the switch operating or drive lever 212 remained stationary, the indicator operating arm 267 was moved together with the mechanism toggle lever 231 and the outturned end 266 moved in the relatively long arcuate slot 265 in the arcuate position indicator 253. This shifts the arcuate position indicator 253 so that an indicia bearing section 309 registers with the window 257 in the cover 258. The section 309 shows that the switch blade means 105 is open and that the mechanism, particularly the coil compression spring 239, is fully charged.

When it is desired that the switch blade means 105 be closed, either the closing coil 299 is energized from a remote position or the closing push button 301 is depressed to rotate the upper latch lever 287 and move its latch hook 291 out of engagement with the latch pin 286. The switch

operating or drive lever 212 no longer is restrained and the switch closing arm 248 of the switch operating member 247 in engagement with the impact member 250 transmits the force of the spring 239 to rotate the switch operating or drive lever 212 and therewith the switch blade means 105 to the switch closed position.

FIGS. 28 and 29 show the relation of certain parts of the overcenter spring means 32 when the switch blade means 105 are closed and the coil compression spring 239 is discharged. While the manually operable handle 33 and the mechanism cam 225 remain in the position to which they had previously been moved, FIG. 26, the mechanism toggle lever 231 was released on release of the upper latch lever 287, as described, with the result that the spring 239 rotates the mechanism toggle lever 231 to the position shown in FIG. 28 and at the same time rotates shaft 106 and therewith the switch blade means 105 to the switch closed position. This is accomplished through the force applied to the switch operating member 247 by the coil compression spring 239 and transmitted to the impact member 250 to rotate the switch operating or drive lever 212 to the position shown in FIG. 29. Here the latch pin 286 is engaged by the latch hook 292 of the lower latch lever 288. Not only are the switch blade means 105 held in the switch closed position by the lower latch lever 288 but also, as previously described, the overcenter toggle mechanism, FIG. 13, serves to hold the switch blade means 105 in the switch closed position.

The outturned end 266 of the indicator operating arm 267 that is carried by the mechanism toggle lever 231 is moved to the position shown in FIG. 29 and carries with it the arcuate position indicator 253 so that a section 310 thereof is visible through the window 257 in the cover 258. Suitable indicia on the section 310 indicate that the switch blade means 105 is closed and that the mechanism including the spring 239 is discharged.

Now, when it is desired to again charge the spring 239 to permit subsequent opening of the switch blade means 105 on release of the lower latch lever 288, the manually operable handle 33 can be swung to the position shown in FIG. 24. This is accompanied by rotation of the mechanism toggle lever 231 to a position about 15° past the center line position representing a line, FIG. 15, interconnecting the axis of the shaft 219 and the knife edge 237. This is accompanied by rotation of the indicator operating arm 267 so that the outturned end 266 rotates the arcuate position indicator 253 to bring section 311 thereof in registry with the window 257 in the cover 258. The section 311 bears indicia indicating that the switch blade means 105 is closed and that the mechanism including the coil compression spring 239 is charged. Now, either on energization of the opening coil 300, FIG. 21, or depression of the opening push button 302, the lower latch lever 288 is released and the switch operating arm no longer is restrained. It engages the impact member 251 to rotate the switch operating or drive lever 212 and break the toggle connection to the switch blade means 105 followed by rotation thereof to the open position. As the switch blade means 105 approaches the fully open position, the foot portion 117' of the L-shaped arm 117 that rotates with the shaft 106 engages the dashpot arm 207 and rotates it in a counterclockwise direction, FIG. 13, to compress return spring 206 and move the piston 204 into the dashpot 201. This cushions the movement of the switch blade means 105 and gradually dissipates some of the kinetic energy incident to its rotation to the open position.

The overcenter spring means 32 can be modified by omitting the latch levers 287 and 288 and the parts associated therewith. When such an arrangement is employed, as soon as the manually operable handle 33 has moved sufficiently far from its lower position, FIG. 13, to cause the spring operating tube 234 to pass the center position, the switch blade means 105 is promptly rotated to the switch closed position. Then the manually operable

handle 33 occupies the position as shown by broken lines in FIG. 13 or is in the upper position. When it is desired to open the switch blade means 105, the manually operable handle 33 is swung to the position shown by full lines in FIG. 13. After the spring actuating tube 234 and associated parts pass the center position, the switch blade means 105 is rotated promptly to the open position.

As pointed out hereinbefore it may be desirable to provide for discharging the coil compression spring 239 when it is latched by the upper latch lever 287, FIG. 21, in a position to operate the switch blade means 105 from the open position, FIG. 13, to the closed position. It may be undesirable to operate the closing push button 301 for discharging the coil compression spring 239, then recharging it and thereafter operating the opening push button 302 to discharge the coil compression spring 239 to operate the switch blade means 105 back to the open circuit position. It is for accomplishing the discharge of the coil compression spring 239 without operating the switch blade means 105 from the position that it occupies that the push button 281 is employed in conjunction with the stop lever 270 and the coupling lever assemblies 312-312' shown in FIGS. 30 to 34 inclusive. The coupling lever assembly 312 is employed in conjunction with the push button 281 to permit discharge of the coil compression spring 239 when the switch blade means 105 occupies the open position while the coupling lever assembly 312' is employed for accomplishing this result when the switch blade means 105 occupies the closed position.

Referring first to FIG. 30, it will be observed that the manually operable handle 33 is shown in the upper position and that the mechanism toggle lever 231 is in the overcenter position where it is held by the upper latch lever 287 as shown in FIG. 21 through the agency of the switch operating or drive lever 212. In this position of the mechanism toggle lever 231 the roller 273, carried by the stop lever 270, has rolled off of the periphery 274 of the mechanism toggle lever 231 and has been rotated in a counterclockwise direction by the torsion spring 272 to place the stop pin 277 in the path of shoulder 279 on the mechanism cam 225. The stop pin 277 in this position prevents rotation of the mechanism cam 225 and thereby prevents rotation of the manually operable handle 33 which rotates conjointly therewith and with the shaft 219.

In order to move the stop pin 277 out of the path of shoulder 279, it is necessary under the assumed conditions to depress the push button 281. Normally the push button 281 is concealed by the cover 284 which may be locked and thus unaccessible except to authorized personnel. On opening of the cover 284, the push button 281 can be depressed to compress spring 283 and engage the tail piece 280 for rotating the stop lever 270 in a clockwise direction to move the stop pin 277 out of the path of shoulder 279. Then it is possible to rotate the mechanism cam 225 and therewith the manually operable handle 33 in a clockwise direction from the position shown in FIG. 30.

The coupling lever assembly 312 now becomes operative under the assumed conditions where the switch blade means 105 occupies the open position. Under similar circumstances with the switch blade means 105 in the closed position the coupling lever assembly 312' becomes operative.

The coupling lever assemblies 312 and 312' are essentially duplicates of each other. Accordingly, corresponding reference characters are applied to corresponding parts. The coupling lever assemblies 312 and 312' are mounted by connecting pins 313-313' on the mechanism cam 225. They are arranged to cooperate with stop pins 314-314' which are stationarily mounted on the adjacent side wall 218, FIG. 14, of the recess operating mechanism support 31. The coupling lever assemblies 312-312' include coupling lever operators 315-315' which are provided with nose portions 316-316' that are arranged to engage the stop pins 314-314', respectively.

5 The nose portions 316-316' are integral with arms 317-317' on the coupling lever operators 315-315'. A tension spring 318, connected to the distal ends of the arms 317-317', biases the coupling lever operators 315-315' against stop pins 319-319' which are carried by the mechanism cam 225. Rotatable with the coupling lever operators 315-315' through the connecting pins 313-313' are coupling levers 320-320' which have hooks 321-321' at their distal ends. The hooks 321-321' are arranged to engage one side or the other of the generally rectangular operating pins 244 which extends laterally from the mechanism toggle lever 231.

10 The coupling lever operators 315-315' are provided with cam followers 322-322' which are arranged to engage a cam 323 that is stationarily mounted on the adjacent side wall 218 of the recessed operating mechanism support 31.

15 In order to release the coil compression spring 239 with the switch blade means 105 in the open position, it is necessary that the push button 281 be held in the depressed position shown in FIG. 31 while the manually operable handle 33 is rotated from its position shown in FIG. 30 through a small angle such as 3°. This is permissible since the stop pin 277 has been moved out of the path of the shoulder 279. On rotation of the mechanism cam 225 to the position shown in FIG. 31, the nose portion 316 of the coupling lever operator 315 is moved out of engagement with the stop pin 314. The rotation of the coupling lever 312 with the mechanism cam 224 is sufficient to bring the hook 321 into engagement with the operating pin 244, as shown in FIG. 31, thereby establishing a direct connection between the manually operable handle 33 and the mechanism toggle lever 231 to which the coil compression spring 239 is attached and against which it reacts.

20 The continued rotation of the manually operable handle 33 in a clockwise direction moves the mechanism toggle lever 231 past the center position whereupon the coil compression spring 239 is released and its energy discharged until the mechanism toggle lever 231 reaches the position as shown in FIG. 32. Here the manually operable handle 33 has been moved to the position shown by broken lines and the cam follower 322 is moved into engagement with the stationary cam 323. Continued movement in a clockwise direction in engagement with the cam 323 rocks the coupling lever assembly 312 in a clockwise direction and rotates the hook 321 out of engagement with the operating pin 244. The final position is shown in FIG. 33 where the manually operable handle 33 is in the lowermost position.

25 When the switch blade means 105 occupies the closed position with the manually operable handle 33 in the uppermost position corresponding to the charged position of the coil compression spring 239, the coupling lever assembly 312' in conjunction with the stop pin 314' operates in the same manner as previously described on operation of the push button 281 to permit the discharge of the energy in the coil compression spring 239 without requiring that the switch blade means 105 be moved from the closed position to the open position.

30 In either case for the discharge of the energy in the coil compression spring 239 it is necessary that the push button 281 be held in the depressed position while the manually operable handle 33 is being moved from the position such as is shown in FIG. 30 to the position as shown in FIG. 31 and thereafter until the mechanism cam 225 has been rotated sufficiently far to maintain the stop pin 277 out of the path of the shoulder 279 or 278 as the case may be.

35 FIG. 35 shows in a somewhat diagrammatic fashion another embodiment of this invention. It includes a metallic closure, shown generally at 325, having a front wall 326, a rear wall 327 and side walls one of which is shown at 328. On the front wall 326 a door 329 is hinged at 330 about a horizontal axis. This is one distinction over the previously described embodiment in which the door 22 is

hinged to rotate about a vertical axis. Upper and lower insulators 331 and 332 are mounted on the inner side of the door 329 and, at their distal ends, they carry a fuse, shown generally at 333, which is essentially the same as the fuse 85 previously described. Upper and lower contact fingers 334 and 335 extend from the upper and lower insulators 331 and 332 and are connected to the terminals of the fuse 333. The upper contact finger 334 has an outturned foot portion 336 for cooperating with an arcuate interlocking contact member 337 that is mounted on one end of switch blade means indicated, generally, at 338 and which may be constructed as described for the switch blade means 105. The switch blade means 338 is arranged to interconnect the fuse 333 with a stationary contact means 339, carried by an insulator 340. A terminal pad 341 extends from the stationary contact means 339 to permit connection of one terminal of an energized circuit thereto. The switch blade means 338 is arranged to be rotated by a rotatable insulator shaft 342 which corresponds to the rotatable insulator shaft 106 on which the switch blade means 105 is mounted. For interrupting the circuit without external arcing a separable contact circuit interrupter, shown generally at 344, is employed. It may be constructed as described above for the circuit interrupter 136.

The lower contact finger 335 is arranged to engage a stationary line terminal 345 which, together with a line terminal pad 346, is mounted on an insulator 347. The circuit between the terminal pads 341 and 346 extends through the stationary contact means 339, switch blade means 338 and the fuse 333.

While the metallic enclosure 325 may contain a single fuse 333 and a single switch blade means 338, the construction may include three fuses 333 and three switch blade means 338 for a three phase installation.

It is desirable, when the door 329 is opened for servicing the fuse 333 to prevent any likelihood of the operator coming into engagement with energized parts of the circuit. With a view to preventing this, a stationary insulating barrier 348 is suitably mounted in the metallic enclosure 325 in parallel spaced relation inwardly of the front wall 326. The stationary insulating barrier 348 is provided with upper and lower openings 349 and 350 through which the contact fingers 334 and 335 project as shown by full lines. In order to close the openings 349 and 350 when the door 329 is opened to the position shown by broken lines, a movable insulating barrier 351 is slidably mounted by suitable means on the stationary insulating barrier 348. The barrier 351 is arranged to be moved to the position shown by broken lines where the upper edge 352 is moved to a position above the upper opening 349 so that it is completely closed off when the upper contact finger 334 has been withdrawn. The barrier 351 has an opening 353 that normally registers with the opening 350 to permit the lower contact fingers 335 to extend into contact engagement with the stationary line terminal 345.

For moving the barrier 351 vertically to close off the openings 349 and 350 in the stationary insulating barrier 348, an ear 356 is secured to the lower end of the movable barrier 351. The ear 356 is connected to the door 329 by linkage, indicated generally at 357. The linkage 357 includes a link 358 that is connected at 359 to the ear 356. At its other end the link 358 is connected at 360 to an arm 361 that is suitably secured to the inner side of the door 329. When the door 329 is swung from its position shown by full lines to the open position, as shown by broken lines, the linkage 357 causes the barrier 351 to move vertically upwardly into a position where the openings 349 and 350 are completely closed off after the upper and lower contact fingers 334 and 335 have been moved out of the openings 349 and 350.

Interphase barriers 362, 363 and 364 are provided between adjacent phases where more than a single phase arrangement is employed. In such case the movable in-

sulating barrier 351 is made up of three conjointly movable parts to straddle the interphase barriers.

The door 329 can be locked in the closed position by a door handle 365 which is arranged to operate a latch member 366 into and out of engagement with a stationary latch member 367 that is carried by the front wall 326. The construction of the door handle 365 and latch members 366 and 367 may be as disclosed in U.S. Beebe et al. Patent 3,055,996, issued Sept. 25, 1962.

When the door 329 is in the closed position and the switch blade means 338 occupies the closed position, it is not possible to open the door 329, even if it is possible to rotate the door handle 365 to the unlatched position. The reason for this is the interlocking relationship between the outturned foot portion 336 of the upper contact finger 334 and the arcuate interlocking contact member 337 at one end of the switch blade means 338.

It will be understood that the overcenter spring means 32 previously described can be employed for rotating the switch blade means 338 between the switch closed and the switch open position. Also, it will be understood that the previously described interlocking mechanisms can be employed in conjunction with the door handle 365 for preventing its operation except under the conditions outlined hereinbefore.

FIG. 46 shows, somewhat diagrammatically, another modification of this invention in which both the fuse and the circuit interrupter means are mounted on the door for movement therewith to the open position. In this figure the metallic enclosure is shown, generally, at 368 and it includes a top connecting box 369, a metallic housing 370 for the circuit interrupting apparatus, and a bottom connecting box 371. They are arranged and constructed as described hereinbefore with respect to the metallic enclosure 10.

The front side of the metallic housing 370 is closed by a door 372 that is hinged to swing about a vertical axis and is mounted as described for the door 22. The door 372 carries upper and lower insulators 373 and 374. An upper contact assembly, shown generally at 375, is mounted on the upper insulator 373. The lower insulator 374 carries a fuse support fitting 376 that is similar to the fitting 96 above described. A fuse, shown generally at 377, is connected at its upper end to the upper contact assembly 375 and is mounted on the fuse support fitting 376 at its lower end. The fuse 377 may be of any suitable type, such as the fuse 85 described hereinbefore, a current limiting fuse, etc.

The upper contact assembly 375 has a rearwardly extending contact extension 378 that is arranged to be engaged by one end 379 of switch blade means 380 which is mounted for rotation with an insulator shaft 381, the construction being similar to that of the switch blade means 105 and the shaft 106 previously described. The other end 382 of the switch blade means 380 is arranged to have contact engagement with stationary contact means 383 that is carried by an insulator 384 which is mounted on a transverse channel 385. A terminal pad 386 extends upwardly from the stationary contact means 383 to permit connection of a cable or bus bar.

In order to interrupt the circuit under normal load current conditions without arcing, separable contact circuit interrupter means, shown generally at 387, is mounted on the upper contact assembly 375. The separable contact circuit interrupter means 387 can be constructed as described hereinbefore for the circuit interrupter means 136. It will be understood that the arrangement and operation of the circuit interrupter means 387 is such that, on operation of the switch blade means 380 from the closed position, shown by full lines, to the open position, shown by broken lines, the current path is transferred to the separable contact circuit interrupter means 387 in which the load current is interrupted. This is followed by rotation of the switch blade means 380 to the open position. On closure of the circuit, the arrangement is such

that the circuit is completed between the contact extension 378 and the one end 379 of the switch blade means 380 rather than through the separable contact circuit interrupter means 387.

The fuse 377 has a lower fuse terminal 390 from which a lower contact finger 391 extends laterally for engagement with a bifurcated end 392 of a stationary line terminal 393. The stationary line terminal 393 is mounted on a line terminal pad 394 which is carried by an insulator 395 that is mounted on a transverse channel 396. The circuit connection by way of a cable or bus bar can be made to the line terminal pad 394.

It will be understood that, while only a single fuse 377 and associated switch blade means 380 have been illustrated, the arrangement can be for either single phase or polyphase depending upon the number of fuses 377 and associated equipment that are employed.

It is desirable that access to the stationary contact means 383 and to the stationary line terminal 393 be prevented when the door 372 is opened. For this purpose there is provided a stationary insulating barrier 397 that is generally Z-shaped with the upper portion being provided with an upper opening 398 to permit the one end 379 of the switch blade means 380 to be rotated therethrough. A lower opening 399 is provided in the insulating barrier 397 through which the lower contact finger 391 projects when the door 372 is closed.

In order to cover the upper opening 398 when the door 372 is opened, an upper movable barrier or shutter 400 is provided having an opening 401 that registers with the opening 398 when the door 372 is closed. Likewise a lower movable barrier or shutter 402 is provided having an opening 403 which registers with the lower opening 399 in the stationary insulating barrier 397 to permit insertion of the lower contact finger 391.

It will be understood that the interlocking arrangement previously described can be employed in conjunction with the operation of the door 372 and a spring operator, such as previously described, can be used for rotating the switch blade means 380 between the closed and open circuit positions. The arrangement is such that the door 372 can be opened only when the switch blade means 380 occupies the open circuit position shown by broken lines. Provision is made for operatively interconnecting the door 372 and the upper and lower movable barriers or shutters 400 and 402 for moving them laterally to close off the upper and lower openings 398 and 399 in the stationary insulating barrier 397 when the door 372 is opened and for restoring them to the positions as shown in FIG. 36 when the door 372 is closed. The shutter operating mechanism previously described can be employed for operating the upper and lower barriers or shutters 400 and 402.

It is advantageous to place both the fuse 377 and the separable contact circuit interrupter means 387 on the door 372. When the door 372 is opened, both of these devices are readily available for inspection and replacement by a relatively unskilled operator. Since it is unlikely that any particular attention need be paid to the switch blade means 380, it is satisfactory to position it, as shown, behind the stationary insulating barrier 397 where access can be had only by authorized personnel.

What is claimed as new is:

1. Metal enclosed switchgear comprising:

a metallic housing having walls with one wall including a door,
means mounting said door on said housing for movement between open and closed positions,
circuit interrupter means mounted on and movable with said door,
stationary contact means in said housing,
switch blade means for interconnecting said circuit interrupter means and said stationary contact means,
and
means interlocking said door and said switch blade

75

means and preventing movement of said door and said circuit interrupter means to open position until said switch blade means is moved to open position.

2. The metal enclosed switchgear according to claim

5 1 wherein:
the circuit interrupter means comprises fuse means, and

means interlocking said fuse means and the switch blade means and thereby prevent opening the door as long as said switch blade means is in the closed position.

3. The metal enclosed switchgear according to claim

1 wherein:
the circuit interrupter means comprises fuse means and separable contact circuit interrupter means is connected in series circuit relation therewith.

4. Metal enclosed switchgear according to claim 2

wherein:
manually operable latch means on the door cooperate with latch means on the housing to latch said door closed, and

means interlock said latch means and the switch blade means and prevent unlatching of said latch means until said switch blade means is moved to the open position.

5. Metal enclosed switchgear according to claim 4

wherein:
the switch blade means is mounted on a rotatable shaft, and

the means interlocking the latch means and said switch blade means include:

a locking cam non-rotatably mounted on said shaft,

a locking lever for operation with said locking cam,

a pawl for operation with the latch means on the door, and

means operatively interconnecting said locking lever and said pawl.

6. Metal enclosed switchgear according to claim 1

wherein:
overcenter spring means are connected to the switch blade means for operating the same between closed and open positions,

a manually operable handle is operatively connected to said overcenter spring means for charging the same,

manually operable latch means on the door cooperate with latch means on the housing to latch said door closed, and

means interlock said latch means and said manually operable handle and prevent unlatching of said latch means until said overcenter spring means is discharged and said handle occupies a predetermined position.

7. Metal enclosed switchgear according to claim 6

wherein:
the manually operable handle is mounted on a rotatable shaft and

the means interlocking the latch means and said manually operable handle include:

a locking cam non-rotatably mounted on said shaft,

a locking lever cooperating with said locking cam,
a pawl cooperating with the latch means on the door, and

means operatively interconnecting said locking lever and said pawl.

8. Metal enclosed switchgear according to claim 1

wherein:
manually operable latch means on the door cooperate with latch means on the housing to latch said door closed,

the switch blade means is mounted on a rotatable shaft,

overcenter spring means are operatively connected to said shaft for rotating said switch blade means between closed and open positions, a manually operable handle rotatable with a shaft is operatively connected to said overcenter spring means for charging the same, and means interlock said latch means and said rotatable shaft including:

a locking cam non-rotatably mounted on each shaft,
a locking lever for each locking cam,
a pawl for the latch means on said door, and
means interconnecting said pawl and said locking levers.

9. The metal enclosed switchgear according to claim 1 wherein:
means mount the switch blade means for rotation about a horizontal axis between open and closed positions, and
means mount the door for rotation about a vertical axis between open and closed position.

10. The metal enclosed switchgear according to claim 1 wherein:

means mount the switch blade means for rotation about a horizontal axis between open and closed positions, and

means mount the door for rotation about a horizontal axis between open and closed positions.

11. Metal enclosed switchgear comprising:

a metallic housing having walls with one wall including a door,

means mounting said door on said housing for movement between open and closed positions,

fuse means mounted on and movable with said door, circuit interrupter means in said housing including separable contacts,

switch blade means for connecting said fuse means and said separable contacts in series circuit relation, and means interlocking said fuse means and said switch blade means and preventing movement of said door and said fuse means to open positions until said switch blade means is moved to open position.

12. The metal enclosed switchgear according to claim 11 wherein the interlocking means includes:

a fuse terminal contact extending from the fuse means, a switch terminal contact extending from the switch blade means in closed position to engage said fuse terminal contact, and cooperating shoulder means on said terminal contacts preventing separation thereof until said switch blade means is moved to open position.

13. The metal enclosed switchgear according to claim 12 wherein:

the switch blade means is mounted on a rotatable shaft, and

the switch terminal contact is arcuate in configuration and maintains interlocking contact engagement with the fuse terminal contact until said switch blade means is rotated to a predetermined position.

14. Metal enclosed switchgear comprising:

a metallic housing having walls with one wall including a door,

means mounting said door on said housing for movement between open and closed positions

fuse means mounted on and movable with said door, terminal contact means extending laterally from said fuse means,

stationary contact means in said housing,

switch blade means for interconnecting said terminal contact means and said stationary contact means,

insulating barrier means movably mounted in said housing and having at least one opening therein through which said terminal contact means extend when said door is in said closed position,

insulating barrier means movably mounted in said

75

housing having an opening therein registering with said opening in said stationary barrier means and through which said terminal contact means extend when said door is in closed position, and means interconnecting said door and said movable barrier means for moving the latter relative to said stationary barrier means to close said opening therein when said door is moved to open position.

15. The metal enclosed switchgear according to claim

14 wherein:

means mount the door for rotation about a vertical axis between open and closed positions, and means mount the movable barrier means for horizontal translatory movement.

16. The metal enclosed switchgear according to claim

14 wherein:

means mount the door for rotation about a horizontal axis between open and closed positions, and means mount the movable barrier means for vertical translatory movement.

17. The metal enclosed switchgear according to claim

14 wherein:

the switchgear is polyphase switchgear with fuse means, contact means and switch blade means individual to each phase and barrier means common to said phases, and

interphase barrier means between adjacent phases.

18. Metal enclosed switchgear comprising:

a metallic housing having walls with one wall including a door,

means mounting said door on said housing for movement between open and closed positions, contact means mounted on and movable with said door, stationary contact means in said housing, a shaft including electrical insulator means rotatably mounted in said housing,

a switch blade carried by said insulator means for interconnecting said contact means on said door when said door is in closed position and said stationary contact means, and

means for rotating said shaft and therewith said switch blade between contact engaged and contact disengaged positions.

19. Metal enclosed switchgear according to claim 18

wherein:

the insulator means is an elongated insulator and the switch blade extends transversely therethrough.

20. Metal enclosed switchgear according to claim 19

wherein:

the switch blade comprises a pair of elongated switch blade members the ends of which are spaced apart and provide contact engaging portions facing each other, and

spring means bias said contact engaging portions toward each other and into engagement with the respective contact means.

21. Metal enclosed switchgear according to claim 19

wherein:

a tubular member extends transversely through the elongated insulator,

the switch blade extends through said tubular member and comprises a pair of elongated switch blade members,

means secure said switch blade members in juxtaposed relation at one end of said tubular member, and spring means reacting between the other end of said tubular member and said switch blade members bias them toward each other.

22. Metal enclosed switchgear according to claim 21

wherein:

the elongated insulator is formed of porcelain, the tubular member is formed of metal, and cement secures said tubular member to said porcelain insulator.

23. Metal enclosed switchgear comprising:

a metallic housing having walls with one wall including a door mounted for movement between open and closed positions,

circuit interrupter means mounted on and movable with said door,

stationary contact means in said housing,

switch blade means for interconnecting said circuit interrupter means and said stationary contact means, overcenter spring means connected to said switch blade means for operating the same between closed and open positions,

a manually operable handle connected to said overcenter spring means for charging the same,

latch means for holding said overcenter spring means in charged condition, and

means for releasing said latch means to permit said overcenter spring means to operate said switch blade means.

24. Metal enclosed switchgear according to claim 23 wherein:

the latch means comprises a pair of latch members one for holding the overcenter spring means in one overcenter charged position to close the switch blade means and the other for holding said overcenter spring means in another overcenter charged position to open said switch blade means, and means are provided for selectively unlatching said latch members.

25. The metal enclosed switchgear according to claim 24 wherein:

the means for selectively unlatching each latch member includes a manually operable member.

26. The metal enclosed switchgear according to claim 24 wherein:

the means for selectively unlatching each latch member includes a remotely operable member.

27. The metal enclosed switchgear according to claim 23 wherein:

stop means prevent operation of the manually operable handle when the overcenter spring means is charged, and

means are arranged to displace said stop means and permit operation of said manually operable handle to move said overcenter spring means past its center position to discharge the same without operating the switch blade means.

28. Means for operating switch blade means between circuit closed and circuit open position comprising:

an operating shaft rotatable about a fixed axis,

a manually operable handle connected to said operating shaft for rotating it from one position corresponding to one position of said switch blade means to another position corresponding to the other position of said switch blade means,

a mechanism cam secured to said operating shaft for rotation therewith and having a pair of circumferentially oppositely facing operating pin engaging shoulders,

a hollow shaft rotatably mounted on said operating shaft,

a mechanism toggle lever secured to said hollow shaft for rotation therewith and carrying an operating pin for engagement by one or the other of said shoulders, overcenter spring means connected to the distal end of said mechanism toggle lever and arranged to be charged by force transmitted from said manually operable handle through said mechanism cam to said mechanism toggle lever when said manually operable handle is rotated from one position toward its other position,

a sleeve rotatably mounted on said hollow shaft, a drive lever secured to said sleeve for rotation therewith and constructed and arranged for operative connection to said switch blade means, and

a switch operating member secured to and rotatable with said hollow shaft for engaging said drive lever to transmit energy stored in said overcenter spring means to said drive lever when said overcenter spring means is operated past its center position.

29. The switch blade operating means according to claim 28 wherein:

the manually operable handle is secured to one end of the operating shaft and the mechanism cam is secured to the other end thereof,

the mechanism toggle lever is secured to the end of the hollow shaft adjacent said mechanism cam and the switch operating lever is secured to the other end of said hollow shaft, and

the sleeve and the drive lever thereon are located between said manually operable handle and said switch operating lever.

30. The switch blade operating means according to claim 28 wherein:

a position indicator is movably mounted with respect to said switch blade operating means,

means on the drive lever operate said position indicator to show its position and thereby the position of the switch blade means, and

means on the toggle lever also operate said position indicator to show its position and thereby the condition of the overcenter spring means.

31. The switch blade operating means according to claim 30 wherein:

the position indicator is rotatably mounted on the hollow shaft between the mechanism toggle lever and the switch operating member.
